STOCKING

Eric Boettcher, Southampton, Pa.

Application October 13, 1953, Serial No. 27,161

Term of patent 3½ years

(Cl. D47—7)

FIG. 3.

FIG. 1.

FIG. 2.

Fig. 1 is a side perspective view of a stocking showing my new design;

Fig. 2 is a fragmentary front elevational view thereof;

Fig. 3 is a fragmentary rear elevational view thereof.

The dominant features of my new design are shown in solid lines in the drawing. The broken lines showing of a stocking is for illustrative purposes only.

I claim:

The ornamental design for a stocking, substantially as shown and described.
